VENETIAN BLIND SLAT AND METHOD OF
MAKING SAME

Richard H. Wright, Cleveland Heights, Ohio

Application February 26, 1945; Serial No. 579,813

4 Claims. (Cl. 160—405)

1

My invention appertains to the art of Venetian blinds.

In recent years Venetian blind slats have been made from metal in lieu of the wood slat commonly used previously, and still used for many of such blinds. Owing to the scarcity of wood under present war conditions, the metal slats for Venetian blinds have found wide acceptance in the trade.

When the metal type of Venetian blind slat is employed, a common practice today is to form this slat of transverse concavo-convex cross section as the slat material is supplied from a roll of thin sheet steel ordinarily used. The forming of the slat in the above manner is designed to give it sufficient rigidity to remain straight when the slats are installed in the Venetian blind unit, yet permitting a certain amount of lateral flexing of the slat as when it may be caught at its end or ends in a curtain or other obstacle, the flexing being of a resilient nature so that the slat will spring back to its original straight form after so flexed.

In the making of Venetian blinds from thin sheet steel material, it is found necessary to use pre-treated steel sheet metal in order that the ultimate slat produced may not be formed with wavy edges. One of the objects of my invention is to do away with the necessity of using the pre-treated steel referred to, and, indeed, I have found that by the article of manufacture and method of my present invention I am enabled to employ soft metal such as aluminum in the production of the Venetian blind slat as will be more fully later on pointed out.

It has been proposed heretofore to make slats of the nature referred to from sheet metal and render the same stiff by forming edge flanges. Under these conditions, however, the slats produced are so stiff that they will not flex for the purposes previously mentioned, and should the end portions strike any obstacle in the raising or lowering of the blind, the entire slat is affected by a permanent bending off the said end or end portions.

In the carrying out of my invention I employ the method of manufacture of the blind slat largely similar to the present method in so far as the material such as aluminum is supplied in rolls of the proper width of material for making the slat and is formed into a curved or concavo-convex cross section transversely thereof the material being cut off in proper length by a cutting mechanism associated with the forming machine to make the required length of slat. In the further

2

carrying out of my invention I have found that when I form the slat material into its curved cross section referred to above the edge portions of the material will wave or kink at intervals and therefore will obviously not retain the straight conformation from end to end that is required for the purposes of the slat use. I therefore have found that if I apply pressure to the longitudinal central portion of the slat material after the forming thereof into the curved cross-section required to provide the necessary stiffness to maintain the slat straight, and by such pressure produce a very slight and almost imperceptible reverse bend of the material at the longitudinal center, I am enabled to eliminate the waving or kinking of the edge portions of the slat material produced by the action of the forming machine that creates the curved cross section mentioned. The reverse bend to which I refer above, as to the direction of reversal, means that the bend is upon an arc in a direction reverse to the arc of curvature of the concave side of the slat, as produced by the forming machine and effected by the passing of the slat material between a convex peripheral roller and a concave peripheral roller.

I have found that by the use of my method I produce a novel article of manufacture in the form of a Venetian slat which is just as effective and advantageously used as those which are today made from thin sheet steel pretreated, my slat having the requisite longitudinal stiffness, and yet being adapted to be flexed in a resilient manner, so that if it is slightly flexed or bent at its ends, it will, by reason of the inherent resiliency, return to its straight condition, much after the manner of the action of the steel slat mentioned at the outset hereof. Moreover, I have found that I can produce my blind slat from relatively soft material such as aluminum, a material far more available at the present time than steel.

A special advantage of my method and article of manufacture lies in the fact that the reverse center bend of my slat construction is scarcely visible to the eye, so that in no way does the method of treatment of my slat for the purposes referred to detract from the appearance of the slat when it is installed in the blind unit for actual use.

A full understanding of my invention will be had upon reference to the following detail description and to the accompanying drawing, the latter illustrating a suitable type of forming machine useful for the practice of the method of my invention, and also showing the form of the material from which my slats are constructed,

as supplied originally, as preliminarily formed to give the slat material a curved transverse cross section, and as secondarily formed to provide the slight longitudinal central reverse bend to which I have previously referred.

Referring to my drawings:

Figure 1 is a top plan view of a preferred form of my machine for practicing my invention.

Figure 2 is a side elevation.

Figure 3 is a view looking endwise of the machine to bring out more clearly the arrangement of the final forming rolls or rollers.

Figure 4 is a view in cross section of the slat material as it is supplied to the machine herein-after described.

Figure 5 is a similar view to Figure 4 but showing the material after the main forming operation of producing the concavo-convex transverse curvature thereof; and

Figure 6 is a view similar to Figure 5 but showing the final condition of the slat material ready for the cutting of the same to slat lengths, the dotted lines in this figure illustrating the action of the reverse bend producing roller.

Figure 7 is a view similar to Figure 3 but showing a slightly modified construction of the invention.

Figure 8 is a sectional view of a modified form of the bending rollers.

Referring to my drawings, I indicate at the outset thereof that the machine which is now described is only one of many types of machines that may be utilized for the practice of my invention.

In its preferred form the machine as illustrated in the drawings comprises a pair of feed rollers 1 which, as shown, are mounted in a bracket A disposed upon the base C, between which rollers the slat material cut to the proper width, usually approximately 2 1/4", is fed, said material being designated B. The material B will be supplied from a suitable roll of such material not illustrated, and when fed between the rollers 1 will be guided somewhat by an upper horizontal roller 12 that engages the upper edge of the material. The slat material as it feeds from the rollers 1 onward through the machine passes over a base plate C to initial forming rollers 2 and 9. The roller 9 is a convex on its surface and the roller 2 is concave.

The rollers 2 and 9 give to the strip of slat material B preliminary slight curved cross section, and the material then passes from the rollers 2 and 9 to the main or primary forming rollers 3 and 10 which are somewhat larger than the rollers 2 and 9 and which give to the material B its ultimate or final concavo-convex curved cross section. From the rollers 3 and 10 the material B passes by a guide roller 4 which is practically in the form of a ball, the peripheral contour of which corresponds with the contour of the general curved cross section of the material B. Thereafter, the material B passes the guide member 4 between guide rollers 5 and 11 which are contoured at their peripheries so that the roller 11 is convex on its surface and the roller 5 is concave, the curvature of these portions likewise corresponding to the now fixed general curved cross section of the material B. As the strip of material B is fed on from the rollers 11 and 5 in the machine, it is received between the final forming rollers 7 and 8. Generally speaking the roller 8 has its periphery or rolling surface straight, whereas the roller 7 is a relatively narrow rimmed roller or peripheried roller with its

periphery very slightly convex. This convexity is slightly exaggerated in Figure 2 of the drawings.

The action of the roller 7 is to produce the slight reverse bend at the central longitudinal portion of the strip of slat material B to which I have previously referred, for the reason that as the material B feeds from the rollers 3 and 10 the edges of the material will become slightly kinked or waved at intervals in the length of such material.

The roller 7 must be subjected to the action of pressure against the central longitudinal portion of the material B in order to effectuate the function which I have described in reference thereto, and this pressure is applied to the roller 7 by means of an adjustable screw mounted in a vertical standard 14 and acting by engagement with a coiled spring 16 to press or exert a force against the carrier member 6 in which the axis shaft 17 of the roller 7 is mounted. The screw 13 provides for adjustment to obtain the desired pressure on the carrier 6 and the roller 7, such that the periphery of the roller 7 by bearing against the central longitudinal portion of the material will produce a very slight bend in a direction of curvature opposite to the arc of curvature of the body of the material B by which the curved transverse cross section of the latter is produced. The standard 14 may be carried on a suitable base plate 18 on which the rollers 8 and 7 may be suitably supported upon their axis shafts. The object especially in using the screw member 13 is to adjust the same so that only the very slightest pressure will be produced on soft metal slat strip material B, just enough pressure to give the central longitudinal bend the required arc.

The arrangement of the roller 7 in operating upon the material B is well shown in Figures 2 and 3, and in respect to Figure 3 I have shown in Figure 7 a similar view illustrating, however, the omission of the spring 16 intermediate the screw 13 and the roll carrier 6. While the construction of Figure 3 is well adapted for employment in conjunction with the material B of relatively soft metal such as aluminum, under some conditions where harder metal is employed, it is desirable to have the screw 13 act directly upon the carrier 6 for producing the desired pressure to form the harder metal with the longitudinal central reverse bend, as I term it in this specification.

In Figure 4 the condition of the material B as it is fed to the rolls 1 of my machine is illustrated. In Figure 5 the illustration of the material is in the form which is produced by the final main forming rollers 3 and 10, and in Figure 6 the material B is illustrated in its condition of actual use to be cut up into the blind slats, Figure 6 showing the main transverse concavo-convex cross sectional form of the strip of material as well as the manner in which the central longitudinal portion is bent to produce the reverse bend feature to which I have heretofore referred.

The small longitudinal bend B' of the material B is formed subsequently to the curved cross section of the body of the said material, see Figure 6. Also, it is noted that the periphery of the roller 7, at its point of bending contact with the strip B, engages a little beyond—to the right of, as seen in Figure 1—the point of peripheral contact of the roller 8, the right end of the strip being under tension by the feed rolls carrying the strip B onward and rightward from the rollers 7 and 8. This enables the roller 7 to effect the proper form-

ing of the reverse bend B' in the processing of the aluminum or relatively soft material as hereinbefore set forth.

When the metal worked by my process is hard, such as thin strip steel, I find it desirable to use, in lieu of the rollers 7 and 8, rollers or rollers 7a and 8a as seen in Figure 8. The roller 7a has an external bending rib 7b surrounding same, and the roller 8a has a matching annular groove 8b so that as the strip B passes therebetween, the bend B' will be formed. The external portions of the rollers 7a and 8a are contoured like the rollers 5 and 11 and the axes of the rollers 7a and 8a will be transversely aligned instead of disaligned, as are those of the rollers 7 and 8.

By the use of my invention, I avoid the necessity of employing the pre-treated strip steel first referred to herein, steel that is longitudinally stretched between the edges thereof along a central line, and which is required to be subsequently stretched at its edges.

The rollers 7a and 8a may act on the strip B after it has been formed into its curved transverse cross section or they may be the forming rollers actually operating to impart such cross section to the strip, in which event they would be substituted for the rollers 3 and 10, respectively, of my machine.

Having thus described my invention, what I claim as new and desire to secure by Letters Patent of the United States, is:

1. The method of producing thin sheet metal Venetian blind slats, which includes the steps of bending by pressure a long strip of thin flexible resilient metal into a transverse concavo-convex uniform cross-section from edge to edge effecting stretching of the side edge portions of the strip and waving at said portions, and applying pressure to the strip of metal along a line centrally and longitudinally thereof to produce slight bending of the metal on an arc opposite to that of the concavo-convex cross section for eliminating waving of the edges of the strip incident to pressure forming of same into its uniform concavo-convex formation, and thereby stretching the central longitudinal portion of the strip to straighten same throughout its entire length.

2. The method of producing thin flexible and resilient sheet metal Venetian blind slats, which includes first bending a long strip of thin resilient metal into a transversely uniform concavo-convex cross section curving in one direction from edge to edge stretching the metal of the

strip along its side edge portions, and then subjecting the strip so formed to pressure along a central longitudinal line of the strip to deform the material thereof on a slight curve cross-sectionally thereof and in a direction reverse to the general concavo-convex curvature before mentioned to stretch the central longitudinal portion of the strip to take out waves at its edges produced by the said concavo-convex bending operation and to straighten the edges while maintaining the resiliency of the strip angularly of its longitudinal axis.

3. The method of making Venetian blind slats which includes the steps of subjecting a long strip of thin flexible and resilient sheet metal of single thickness from longitudinal edge to opposite longitudinal edge, to pressure to bow the same to concavo-convex form in cross section, and pressure rebending the metal of the slat along a narrow longitudinally central area the entire length of the slat but in a direction opposite to the arc of curvature produced by said bowing to eliminate waving of the slat at its longitudinal edges.

4. As a new article of manufacture, a Venetian blind slat comprising a slat length strip of thin flexible and resilient sheet metal of single thickness, the body of which is bowed transversely of its longitudinal axis into concavo-convex cross section with all portions of said cross section from edge to edge on a single relatively large arc of curvature except the central longitudinal area of the slat from end to end, the latter having a narrow shallow bend therein of a depth approximating that of the thickness of the metal and the cross sectional arc of which bend extends in a direction opposite that of the large arc of curvature of the above mentioned cross sectional formation of the body of the slat.
